LAWN EDGER ATTACHMENT FOR SELF-PROPELLED LAWNMOWERS

Robert A. Julian, 1608 Brenda Drive,
Bellevue, Nebr. 68005

Filed July 3, 1974, Ser. No. 486,152

Term of patent 14 years

Int. Cl. D8—03; D15—03

U.S. Cl. D40—1 A

FIG. 1 is a front perspective view of a lawn edger attachment for self-propelled lawnmowers, showing my new design;

FIG. 2 is a front elevational view thereof to an enlarged scale;

FIG. 3 is a rear elevational view thereof to an enlarged scale;

FIG. 4 is a sectional elevational view thereof to an enlarged scale taken along the line 4—4 in FIG. 2; and

FIG. 5 is an end elevational view thereof to an enlarged scale.

I claim:

The ornamental design for a lawn edger attachment for self-propelled lawnmowers, as shown.
